CLAIM

The ornamental design for an adapter for using a power tool battery with other equipment, as shown and described.

DESCRIPTION

FIG. 1 is a front elevational view of the adapter for using a power tool battery with other equipment showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front and upper right perspective view thereof shown with a power tool battery. The broken line showing of the power tool battery is included for the purpose of illustrating environmental elements only and forms no part of the claimed design.

FIG. 1

FIG. 2

FIG. 3

FIG. 4
